UNITED STATES PATENT OFFICE

2,639,682

SEWING-MACHINE ATTACHMENT

Barnhardt A. Taylor, Columbia, S. C., assignor to
 The Greist Manufacturing Company, New
 Haven, Conn., a corporation of Connecticut

Application September 8, 1950, Serial No. 183,825

10 Claims. (Cl. 112—115)

1

This invention relates generally to sewing machines and more particularly to attachment means for a sewing machine whereby buttons may be sewn onto the fabric.

One object of this invention is to provide means for oscillating a button so that a vertically reciprocating needle in a sewing machine may be used to sew the button in place, the throw or travel of the button during the operation being equal to the distance between a pair of holes in the button adapted to receive the attaching thread.

Another object of the invention is to provide a device which will carry out the above mentioned operation and wherein the button is securely held against shifting relative to the oscillating lever, so that accurate registration of the button is maintained after the same has been properly set, thus avoiding breakage of the sewing machine needles.

Another object of this invention is to provide adapters which can be used with a buttonholer attachment of the type disclosed in the patent issued to Almquist under No. 2,482,607, whereby said buttonholer attachment is converted to a button sewing attachment means.

And a last object to be mentioned specifically is to provide a device of the character mentioned above which is relatively inexpensive and practicable to manufacture, which is simple and safe to use, and which will give generally efficient durable service.

With these objects definitely in view, this invention resides in certain novel features of construction, combination and arrangement of elements and portions as will be hereinafter described in detail in the specification, particularly pointed out in the appended claims, and illustrated in the accompanying drawings which form a material part of this application, and in which:

Figure 1 is a view, in perspective, of the complete button attachment means, ready to be secured in place on a sewing machine;

Figure 2 is a longitudinal vertical sectional view taken substantially on the line 2—2 of Figure 1;

Figure 3 is an enlarged fragmentary horizontal sectional view taken substantially on the line 3—3 in Figure 2;

Figure 4 is a top plan view of an insert member comprising part of the pivot means for connecting one pair of the first and second levers herein-after described;

2

Figure 5 is a vertical longitudinal sectional view of the insert member shown in Figure 4;

Figure 6 is a view, in perspective, of the button holder;

Figure 7 is a top plan view of the button holder;

Figure 8 is a vertical sectional view taken on the line 8—8 in Figure 7; and

Figure 9 is a fragmentary plan view of a section of sheet material with a button secured thereon by threads, in the normal use of this invention.

Fig. 10 is an enlarged sectional view on line 10—10 of Fig. 2.

Similar characters of reference designate similar or identical elements and portions throughout the specification and throughout the different views in the drawings.

Referring now to the drawings in detail, this invention includes apparatus similar to a buttonholer attachment of the character illustrated in Figures 1, 2 and 3, although the specific buttonholer structure illustrated need not be employed in this invention, and the following description will, therefore, relate to the essential elements of any such sewing machine attachment to be used

25 with the adapters illustrated separately in Figures 4—8. The essential elements include a frame comprised of an attachment clamp 10 whereby the device may be secured to the pressure bar of a conventional sewing machine, a base plate 12 which may have upraised lateral flanges 14, bearing blocks 16 for a transverse shaft 18, and an actuating arm 20 freely pivoted at one end on the shaft 18 and bifurcated at the other end 22 to straddle the needle clamp. A spring biased 30 pawl 24 is pivotally mounted on the arm 20 and engages a ratchet 26 to drive the rotary cam 28 with an intermittent motion as the needle clamp is moved in vertical reciprocation.

A cam follower 30 is mounted on a first lever 32 which is pivoted on the base plate 12 by what will be hereinafter referred to as pivot means 34. The first lever 32 carries the pin 36 having a reduced lower terminal 38 extending beneath the first lever 32 and, through the agency of the insert member 10 hereinafter described more fully, connects the first lever 32 with the second lever 39. It will be noted that the levers 32 and 39 each move about a vertical axis, the second lever 39 being mounted on the pivot pin 40. In other words, one pair of ends of the first and second levers 32 and 39 are pivotally secured together.

45 The pivot pin 40 is carried on a member 42 which is slidable longitudinally of the plate 12, this member 42 having an arm portion with teeth 44 50 engageable with a flange portion 48 of a fixed

55

plate 50, when the member 42 is manually shifted by a handle 46 rigidly mounted thereon and extending laterally of the device. A coil spring 52 is compressed between a portion of the member 42 and a washer 54 secured to the upper end of the pivot pin 40, so that this pivot pin is biased upwardly while allowing the member 42 to be shifted so that the teeth 44 selectively engage the flange portion 48. An elongated slot 56 is provided in the plate 12 for the lower end portion of the pivot pin 40 it will be understood that adjustment of the member 42 longitudinally of the plate 12 will cause an increase and decrease of the throw of the end 58 of the second lever 39 remote from the pin 36. This last mentioned end of the second lever 39 is bifurcated and extends substantially beneath the bifurcated end 22 of the arm 20, the furcations carrying laterally extending trunnions 60 upon which a centrally apertured plate 62 is pivotally mounted, as best shown in Figure 2, the central aperture of the plate 62 being shown at 64, and this plate ordinarily having upraised side banges into which the trunnions 60 are inserted.

A plate 66 is pivoted, as indicated at 67 upon the main framework of the device, and this plate 66 carries a leaf spring 68 which urges the insert member 70 upwardly into position in an aperture 78 provided in the second lever 39. The insert member 70 is provided with a flange 72 which limits the upward movement of the insert relative to the apertured second lever 39, so that this insert fits beneath the first lever 32, and a slightly elongated recess 74 is provided in the upper face of the insert member 70, together with a larger recess 76, arranged coaxially therewith to accommodate a ratchet wheel 77 conventionally provided in devices of this character, although this ratchet wheel 77 is not functional with the instant invention. The aperture 78 in the second lever 39 has already been mentioned, this aperture being dimensioned and shaped to receive the insert 70 snugly.

The adapters used with the structure described in some detail above include the insert member 70 and the buttonholder illustrated in detail in Figures 6, 7 and 8 and illustrated as used in Figures 1 and 2. The buttonholder includes a plate 80 having upwardly inclined opposing handles 82, extending outwardly from vertical sides of the plate 80, which plate will ordinarily be rectangular in shape, although not necessarily so. The plate 80 has a central aperture 84 which will have a pair of parallel sides, and the central aperture 84 is in communication with a larger recess 86 adapted to receive a button. Upwardly extending flanges 88 on two sides of the aperture 84 and parallel to each other fit into the central aperture 64 of the member 62. The buttonholder may be slid longitudinally of the plate member 62, with the flanges 88 sliding along the aperture 64, as clearly indicated in Figure 2.

The operation of this invention will be clearly understood from a consideration of the foregoing description of the mechanical details thereof, taken in connection with the drawings and with the above recited objects. In recapitulation, and by way of still further explanation, a button 90, having at least one pair of holes 92 can be sewn by thread 94 onto sheet material or fabric 96, using the conventional sewing machine, with this attachment secured thereon. The button 90 is shown in position in the buttonholder, in Figure 2. The arm 20 causes the cam 28 to rotate intermittently and the cam follower 30 actuates the

first lever 32 and reciprocates the pin 36 with its reduced end 38 extending into the member 70 and causing reciprocation of the second lever 39. The insert member 70 does not move longitudinally of the plate 12, but the throw of the second lever 39 can be adjusted by moving the pivot pin 40 by means of the handle 46, thus permitting use of the device with buttons having differently spaced holes 92. The buttonholder may be moved along the opening 64 of the plate 62 so that a second pair of holes in a button may be used without difficulty.

Having described the invention, what is claimed as new is:

1. A sewing machine attachment for attaching buttons having two or more apertures, comprising a supporting frame, a first and a second lever, pivot pins to mount said levers on said frame for oscillatory movement about vertical axes, pivot means connecting one pair of ends of said levers, means to oscillate the first lever and thereby effect oscillation of said second lever, a cloth-engaging foot carried by said second lever, and a buttonholder removably secured to said foot to oscillate therewith.

2. A sewing machine attachment for attaching buttons having two or more apertures, comprising a supporting frame, a first and a second lever, pivot pins to mount said levers on said frame for oscillatory movement about vertical axes, pivot means connecting one pair of ends of said levers, means to oscillate the first lever and thereby effect oscillation of said second lever, a cloth-engaging foot carried by said second lever, and a buttonholder removably secured to said foot to oscillate therewith, one of said pivot pins being shiftable longitudinally of the second lever to adjust the transverse throw of said one end so that buttons having differently spaced holes may be accommodated.

3. A sewing machine attachment for attaching buttons having two or more apertures, comprising a supporting frame, a first and a second lever, pivot pins to mount said levers on said frame for oscillatory movement about vertical axes, pivot means connecting one pair of ends of said levers, means to oscillate the first lever, and a buttonholder removably secured to one end of the second lever to oscillate therewith, said second lever having a portion with an opening at said one end, said buttonholder comprising a plate having a central aperture registering with said opening, upraised members on the plate and engaging said lever at the sides of said opening, said plate having a recess on the underside thereof registering vertically with said central opening and adapted to receive a button.

4. An attachment according to claim 3, and wherein said plate has opposed outwardly and upwardly extending handles.

5. An attachment according to claim 1 and wherein said button holder is adjustable longitudinally of the second lever.

6. Cooperating adapters for a buttonholer attachment having a frame and a first and a second lever mounted thereon for oscillatory movement with pivot means connecting one pair of ends of said levers and a feeding foot on the second lever, one of said adapters comprising means to hold said second lever against movement longitudinally of the frame during operation, and the other adapter comprising a button holder secured to said feeding foot.

7. An attachment according to claim 1 wherein said pivot means for connecting the levers com-

prises an insert removably connected to the second lever, and said insert is provided with an opening to receive a pinion carried by the first lever.

8. A sewing machine attachment comprising a supporting frame, a lever pivotally mounted on the frame, means for oscillating said lever, a second lever pivoted on the frame and connected to the first lever to be oscillated thereby, said connection including a shaft on said first lever having a pinion thereon and a member removably secured to the second lever provided with an opening having a smooth interior wall freely receiving said pinion to permit idle rotation of the pinion, and a button holder carried by said second lever to be oscillated thereby.

9. A sewing machine attachment comprising a supporting frame, a lever pivotally mounted on the frame, means for oscillating said lever, a second lever pivoted on the frame and connected to the first lever to be oscillated thereby, said connection including a shaft on said first lever having a pinion thereon and a member removably secured to the second lever provided with

an opening having a smooth interior wall freely receiving said pinion, said second lever having an opening therein, and said member comprising an insert removably received in said last-named opening, and a button holder carried by said second lever to be oscillated thereby.

10. A sewing machine attachment comprising a supporting frame, a lever pivotally mounted on the frame, means for oscillating said lever, a second lever pivoted on the frame and connected to the first lever to be oscillated thereby, said connection including a shaft on said first lever having a pinion thereon and a member removably secured to the second lever provided with an opening having a smooth interior wall freely receiving said pinion, a button holder carried by said second lever adjacent the end thereof, and means for adjusting the pivot on said second lever longitudinally of the frame to vary the amplitude of oscillations of the second lever.
